COMBINED SALT AND PEPPER SHAKER

Joseph Ultimo, 4951 Warwick Ave., Chicago, Ill.

Filed Jan. 11, 1962, Ser. No. 68,261

Term of patent 14 years

(Cl. D44—22)

FIG. 1.

FIG. 2.

FIG. 3.

FIGURE 1 is a perspective view of a combined salt and pepper shaker showing my new design;

The essential feature of my design resides in the combination in the combined salt and pepper shaker of a pair of apparently intersecting but separated passages for salt and pepper, respectively, and transparent side walls revealing said passages to view.

I claim:

The ornamental design for a combined salt and pepper shaker substantially as shown and described.
